UNITED STATES PATENT OFFICE

JOHN J. QUEEN, OF CHARLOTTE, NORTH CAROLINA

MEANS FOR REGULATING THE LEVEL OF FLUID IN SIZING VATS AND THE LIKE

Application filed April 25, 1927. Serial No. 186,546.

This invention relates to means for regulating the level of the fluid in the vats of sizing machines, and more especially to the preventing of a superfluous amount of the sizing fluid from entering the sizing vat.

I am aware that heretofore means have been employed to prevent the level of the fluid in sizing vats from becoming too high, which means comprises an overflow chamber 10 into which the superfluous amount of the sizing fluid runs, and from this overflow chamber the superfluous amount of sizing fluid is pumped into the main reservoir supplying the vat with the sizing fluid.

15 An object of my invention is to provide means for automatically controlling the flow of the sizing fluid into the vat of a sizing machine, and at the same time prevent evaporated steam from entering the vat.

20 Another object of my invention is to provide means causing the minimum amount of fluid to enter the sizing vat of a slasher.

Some of the objects of invention having been stated, other objects will appear as the 25 description proceed, when taken in connection with the accompanying drawings, in which—

Figure 1 is an end elevation of the sizing vat of a slasher, showing my invention attached thereto;

Figure 2 is a side elevation, looking from the left hand side of Figure 1;

Figure 3 is a plan view of the vat of the slasher, with the squeeze rolls, warp rolls, 35 and other equipment removed for the better showing of the coils in the bottom thereof;

Figure 4 is an enlarged detail view, partly in section of the control valve;

Figure 5 is a view taken along the line 40 5—5 in Figure 4.

Referring more particularly to the drawings, the numeral 10 indicates the sizing vat of a slasher, which has the squeeze rolls 11, 12, 13, and 14 mounted for rotation therein, 45 and which also has the warp rolls 15 and 16 suitably mounted at one side thereof. The rack 17 for holding the emerge roll is also shown, together with the means 18 and 19 for regulating the pressure between the squeeze rolls.

The numeral 20 indicates the hood which is connected to the pipe 21 for taking off the vapors from the sizing vat. All of the above-mentioned parts are conventional, and a further description of the same is not deemed necessary.

In the conventional slasher there is the pipe 22 leading from the supply tank (not shown) for supplying the sizing fluid to the vat 10. It is in this pipe line that I place a 60 part of my invention for regulating the flow of the sizing fluid to the vat 10. Above the valve 23 I place the T-member 24 to which is threadably secured the hollow T-member 25, and leading downwardly from this latter 65 T-member is the union 26 which is threadably secured to the elbow member 27, and secured to the elbow member and also connected to the pipe line 22, is the T-member 28, 70 all of the said members 24 and 28 being hollow to permit the flow of the fluid therethrough. The main pipe line 22 extends downwardly from the T-member 28 into the sizing vat 10.

Below the opening in the T-member 25 75 which leads to the member 24, there is secured the valve seat 30 in which is seated the needle valve 31, and secured within the upper end of the member 25 is the hollow plug 32, the valve stem 33 running therethrough and thru the packing 34 and piercing a hole in the nut 35, which nut is threadably secured around the exterior of the plug 32, and fitting between the upper end of the member 25 and the nut 35 is the support 36, 85 which is forked at its upper end for the reception of the lever 37, which lever is held in position loosely by means of the bolt 38, and secured in one end of the lever 37 is the eye-bolt 39 which adjustably secures the valve stem 33 to the lever, and in the other end of the lever 37 is a similar eye-bolt 40 which adjustably secures the float rod 41 to the lever 37.

This float rod 41 extends downwardly into 95 a float chamber 42 and is secured to the float 43 in the float chamber. This float chamber is secured to the vat 10 by means of the pipe 44 which is connected to and communicates with the lower portion of the float 100

chamber, and this pipe 44 is threadably secured in a hole thru the side of the vat 10, near the bottom thereof, and communicates with the interior of the vat 10, thereby allowing the fluid in the vat to flow into the float chamber and there assume the same level which it has in the vat 10, thus causing the float 43 to have a tendency to remain at a point approximately on a level with the top of the fluid in the vat 10.

In addition to the float controlled means for limiting the amount of fluid which may enter into the vat, I have provided additional means to affect the level of the sizing fluid, which consists of improved means of introducing the steam into the coil of piping in the bottom of the vat. Heretofore the steam has been introduced into one side only of the vat, and this has caused one side of the fluid to be heated to a greater degree than the other side. I have provided means for introducing the steam into both sides of the vat and in this way both sides of the vat are heated to the same degree. The steam is introduced by leading the steam intake pipe 45 into the larger pipe 46, the larger pipe extending downwardly, and from the top portion of this larger pipe there extends upwardly and inwardly the pipe 47, which pipe 47 is connected by suitable connections to the pipe 48 which runs to both sides of the vat and connects to the downwardly extending pipes 49 and 50, these pipes 49 and 50 being connected to the U-shaped perforated pipe 51, thus allowing the live steam to escape thru the perforations in the pipe 51. If the pipes 45 and 47 were connected directly together, as has heretofore been done, it would mean that a large quantity of condensed steam would be introduced into the vat with the live steam, but by providing the larger section 46, and leading the larger section for some distance to a suitable steam trap, the water is caught in this larger section, and thus is prevented from entering the vat and mixing with the sizing fluid.

In the old method of controlling the level in the vat wherein the overflow was allowed to flow into an overflow chamber and from thence pumping it back into the supply tank, it was not necessary and imperative to prevent this great amount of condensed steam from entering the vat, but with my improved means of regulating the level in the vat, it is imperative that the level be prevented from getting too high, as the float controlled means only regulates the amount of fluid coming into the vat.

I have not shown and described the steam trap in detail, as I prefer to employ the conventional steam trap, which is indicated by the numeral 52 in the drawings.

In the drawings and specification I have set forth a preferred embodiment of my invention, and although specific terms are em-

ployed, they are used in a generic and descriptive sense only, and not for purposes of limitation, the scope of the invention being set forth in the appended claim.

I claim:

In a slasher, a sizing vat through which material is adapted to be passed to have sizing applied thereto, a source of sizing supply, a pipe connected to said source of sizing supply and extending to the vat, a pipe leading from one side of the vat at a point below the ordinary level of the sizing fluid, said pipe leading into a float chamber, a float mounted in said float chamber, a valve in the pipe leading from the source of sizing supply, connections between the float and the said valve whereby the valve is adapted to be opened when the level in the sizing vat sinks to a predetermined point, and to close the valve when the level in the sizing vat rises to another predetermined point.

In testimony whereof I affix my signature.

JOHN J. QUEEN.
